UNITED STATES PATENT OFFICE.

DOMINIQUE DI NATALE, OF PARIS, FRANCE.

STYLUS HOLDER.

Application filed May 4, 1923. Serial No. 636,631.

To all whom it may concern:

Be it known that I, DOMINIQUE DI NATALE, engineer, citizen of the French Republic, residing at Paris, Department of the 5 Seine, in France, have invented certain new and useful Improvements in or Relating to Stylus Holders, of which the following is a specification.

This invention has for its object improvements in the diaphragms of talking machines, more especially as regards the mounting of the stylus for reproducing apparatus. The stylus is generally clamped at the end of a rod which is introduced into 15 a socket for the purpose in the arm which is intended to transmit the vibrations of the membrane. Securing of this rod in position is effected by means of a set-screw. In spite of this arrangement the stylus is still 20 subject to a certain amount of play which is injurious to the sounds emitted by the reproducing apparatus.

According to the invention this inconvenience is avoided by mounting the stylus in 25 such manner that absolute rigidity is obtained at the extremity of the arm to which the stylus is applied. The stylus is introduced into a recess formed at the point of a socket which is adapted to screw onto the 30 diaphragm arm. The stylus is provided with a groove or recess to receive the spun-over end of the socket against the bottom of which recess the upper end of the stylus abuts and the length of which is exactly 35 determined for this purpose. As the socket is screwed onto the end of the diaphragm arm the stylus has no play and the clearness and intensity of the reproduction is considerably improved.

40 A constructional modification of the mounting is also provided in which the screw threaded socket can be inverted, the socket carrying the stylus being provided with a screwed end and the amplifying arm of the 45 diaphragm is provided with a screw threaded opening. In another constructional form the socket carrying the stylus is provided with a number of longitudinal slots which permit of its engagement on the 50 smooth part of the amplifying arm, the resultant elasticity of the slots ensuring perfect clamping.

The accompanying drawing shows by way of example different constructional 55 forms of the invention.

Figure 1 shows a stylus carrying arm adapted to the new mounting.

Figure 2, drawn to an enlarged scale, shows a section of the mounting above referred to.

Figure 3 is a constructional modified form of the arrangement of Figure 2.

Figures 4 and 5 are constructional modifications of the arrangement shown in Figures 2 and 3.

The arm 1 is of the usual form of diaphragm arm with the difference that the screw threaded portion 2 which is generally intended to receive a protecting cap for the stylus is in the present case used to receive the socket which carries the stylus.

The lateral clamping screw usually employed in these arms is not required in a construction in accordance with the present invention. The stylus 3 is provided at any suitable part of its length with an annular groove 4. It is mounted in a socket 5 screw threaded as at 6 so that the said socket can be screwed onto the screw threaded portion 2. The socket is provided at 80 its lower part with a recess into which the body or attaching portion of the stylus 3 is introduced. The free edge of the socket adjacent this recess is spun over or otherwise caused to engage with the groove 4 in the stylus 3 and the body of the stylus is cut to a definite length so that the inner end abuts against the inner end of the containing recess.

In the constructional form shown in Figure 3, the mounting of the stylus is exactly the same. Only the socket is shown as being slightly modified, the modification consisting in that its inner part is screw threaded in such manner as to receive the 90 cap 7 intended to protect the stylus against shocks or vibrations while not in use. In this construction it is advantageous to provide the inner part of the socket with a shoulder 8 so as to serve as a stop for the 95 cap 7.

In the construction shown in Figures 4 and 5, the stylus 3 is always mounted in a socket 5 having in its interior a space the length of which corresponds exactly to the 105 length of the body of the stylus and against the inner end which the inner end of the body abuts. The edge of the socket is spun over or otherwise caused to engage in the groove 4.

In Figure 4, the amplifying arm of the diaphragm terminates in a fitting in which is provided a screw threaded hole 9 into which is screwed a screw threaded portion 10 projecting from the socket carrying the stylus. This fitting is machined along the face 11 corresponding to the shoulder 12 of the stylus socket. The stylus is then clamped between two pieces which insures 10 its rigidity once it is placed in position.

In the constructional form shown in Figure 5, the end of the amplifying arm, instead of being provided with a projecting screw threaded portion as in Figure 1, is 15 provided with a smooth portion 2'. The socket carrying the stylus is provided with a number of slots as shown at 13.

This construction of the socket allows for 20 a certain elasticity thereof. The stylus socket or carrier is bored to a diameter corresponding to the smooth portion 2' so that it can be sprung or forced into position on the projecting portion 2', the portions between the slots yielding for this purpose. Efficient clamping of the stylus carrier is thus insured by the elasticity of the 25 material between the slots.

It should be understood that if so desired 30 a protecting cap, which may have an interior smooth bore or a screw threaded bore, may be provided so that it can be pushed onto or screwed onto the exterior

surface of the stylus carrier during the periods in which the apparatus is not being used.

The various constructional forms of the mounting in accordance with the present invention can be applied to all known types of diaphragms without limitation to the example in Figure 1 and the constructional 40 details can be varied according to the different types of diaphragms or other accessory conditions and that the stylus is not intended to be formed of any particular material because, if desired may be of any 45 suitable nature and form within the scope of the present invention. The point of the stylus intended to transmit the vibrations from the membrane may be formed of any 50 suitable material or substance.

Claim:

In a device of the character described, a socket member provided in the outer portion with an inwardly extending recess, a stylus the body portion of which is arranged in the recess and also provided with an annular groove, and the outer portion of the socket adjacent the recess being pressed inwardly and engaged in the groove to retain the inner end of the stylus body 55 in contact with the inner end of the recess.

In testimony whereof I affix my signature.

DOMINIQUE DI NATALE.
